POSTAGE STAMP AFFIXING MACHINE

John J. Whinton, Hamilton Beach, Ontario, and
John Henry Morris, Hamilton, Ontario, Canada

Application July 2, 1948, Serial No. 36,588

1 Claim. (Cl. 216—30)

1

This invention relates to a machine for severing postage stamps from a roll and affixing them to envelopes or other mail matters, the device thus forming a stamp applying and affixing machine.

One important object of this invention is to provide a simple and efficient hand operated machine of this class.

A second important object of this invention is to provide a machine for the purpose set forth especially adapted for use in offices having small and varying numbers of letters to be mailed from day to day or from one mail time to another.

A third important object of this invention is the provision of novel means for feeding stamps from a roll to a severing and applying device.

A fourth important object of the invention is the provision of a novel and improved stamp severing and affixing device.

A fifth important object of this invention is to provide novel means whereby an exhausted roll of stamps may be readily replaced by a fresh one.

A sixth important object of the invention is to provide a novel means for moistening the corner of an envelope to which the stamp is to be applied.

With the above and other objects in view, the invention consists in general of certain novel details of construction and combinations of parts hereinafter fully described, illustrated in the accompanying drawings and particularly claimed.

In the accompanying drawings like characters of reference indicate like parts in the several views, and:

Fig. 1 is a side elevation with the front side plate removed, the view being partly in section.

Fig. 2 is a plan view of the invention.

Fig. 3 is a side elevation thereof.

Fig. 4 is a section on the line 4—4 of Fig. 1.

Fig. 5 is a section on the line 5—5 of Fig. 1.

Fig. 6 is an enlarged detail plan view partly in section.

Fig. 7 is a perspective view of the stamp chute or guide.

Fig. 8 is a view similar to Fig. 1 but showing the parts in a second portion.

Fig. 9 is an enlarged detail section on the line 9—9 of Fig. 2.

Fig. 10 is a perspective view of the means for cutting and applying the stamps.

Fig. 11 is a section on the line 11—11 of Fig. 1.

In the invention as shown in the drawings there is disclosed a base 10 having at its rear portion upstanding side walls 11 projecting in

2

parallelism from the side edges of the base. In the lower part of these side walls toward the rear thereof there are provided alined bearings 12 wherein is journaled a shaft 13 having a feeding roll 14 fixed thereon. The operation of this feed roller feeds the stamps and its circumference is such as to be a multiple of the width of the stamps to be fed thereby. The feed roller is actuated by a step-by-step movement, each 10 step advancing one stamp past the roll. To effect this step-by-step movement there is fixed on the shaft 13 a face ratchet wheel 15 the spacing of the teeth of which is such that the advance of one tooth effects the advance of one stamp by the feed roll. Journalled on the shaft 13 is a pawl member 16 which is urged by a spring 17 into engagement with the ratchet wheel 15. The face end of the pawl 16 is pivoted to an arcuate arm or lever 18 intermediate the ends 15 of the latter as at 19. A tension spring 20 connects the forward end of the lever 18 with the pawl 16 intermediate the ends of the latter. The forward end of the lever 18 is provided with a manipulating button 21. A spring check pawl 22 is fixed to a wall 11 and engages the ratchet 15 to prevent backward movement of the latter. Now considering Figs. 1 and 8, it will be seen that the normal position is that shown in Fig. 1 and the lever 18 is moved backwardly so that the pawl 16 will revolve around the ratchet for the space of one tooth. Then if the lever 18 is moved forwardly the ratchet is turned to the extent of one tooth and the feed roll is rotated to advance one stamp.

35 In order to ensure proper feeding it is necessary that the stamp strip be pressed firmly against the feed roll and to that end the walls 11, above the shaft 13 are provided with slots 23 wherein are mounted vertically slidble bearings 24 supporting a shaft 25. On the shaft 25 is mounted an idler roll 26 which is urged toward the feed roll by a spring 27. The springs 27 are held beneath plates 28 secured to the side walls by screw bolts 29 so that, by adjustment of the 40 bolts, the tension of the springs may be regulated. At 30 is a casing wherethrough passes a removable shaft 31 for supporting a spool or roll 32 of stamps. This casing has a lipped opening 33 so that the strip of stamps may pass out of the opening, be fed around the idler roll and the between the idler roll and the feed roll.

45 Provision is made to facilitate the threading of the stamp strip between the feed and idler roll. To this end pivots 34 extend into the walls 11 rearwardly of the shaft 25 and on these pivots 34

are pivoted the arms 35 of a U-shaped lever having an operating handle 36. The forward ends of the arms 35 lie under the ends of the shaft 25 so that depression of the handle 36 raises the shaft 25 and thus lifts the idler roll allowing space for free threading of the stamp strip.

In order to guide the stamp strip to the cutting and applying station from the rolls there is provided a stamp chute best seen in Fig. 7. This chute consists of a flat strip of metal 37 having an opening 38 therein so that the rolls may engage the stamp strip through this opening. Curved in flanges 39 hold the stamp strip from moving sideways of the chute.

The stamp chute terminates forwardly at an opening 40 formed in a stationary knife blade 41 which is secured transversely of the machine between the walls 11. At 42 is a moveable knife blade which has one end pivoted at one end of the blade 41, the pivot consisting of a screw carrying a spring 43 which urges the blade 42 into close contact with the blade 41 thus providing proper shearing action on the stamp strip. In order to actuate the blade 42, which is normally held depressed at its free end by a spring 44, there is provided a longitudinally extending lever 45 pivoted at 46. The forward end of the lever 45 extends beneath the blade 42. The rear end of the lever 45 is pivoted to the lower end of a plunger 47 the upper end of which engages beneath the arm 18. This plunger is provided near its upper end with a slot 48 and a pin 49 passes through this slot into a side wall thus holding the plunger upright. Extending laterally from the knife 42 adjacent the upper edge thereof is a presser plate 50.

In order to place envelopes in proper position for applying stamps there is provided a tubular guide having a lower table 51 and an upper table 52 hingedly connected at one edge as shown at 53 and held releasably in spaced relation at the other edge by a latch 54. The forward end of the lower table is cut away as at 55 to allow passage of the presser plate and also to allow passage of the upper end of an inclined endless belt 56 trained over shafts 57 extending across a water tank 58, the belt serving to wet the corner of any mail matter pushed through the guide.

What is claimed as new, is:

In a stamp affixing machine, a frame including spaced side walls, stamp feeding mechanism comprising a shaft supported in said side walls, a feed roller on said shaft, a face ratchet on said shaft operable when actuated to rotate the feed roller, a pawl rotatable on said shaft and spring urged into contact with said ratchet, an operating arm pivoted intermediate its ends to the free end of the pawl, a biasing spring connecting the rear end of the operating arm to the pawl intermediate the ends of the latter, a guide chute leading from said feeding mechanism and terminating at a fixed knife slot, a vertically movable combination cutting and applying member adjacent said fixed knife slot, a lever pivoted intermediate its ends and having one arm engaging said movable cutting and applying member, a plunger having its upper end engaged by the operating arm and its lower end pivoted to the remaining arm of said lever, an idler roller resting on said feed roller, and springs urging said idler roller against said feed roller, whereby a downward movement of said operating arm will perform the operation of cutting, moistening and applying the stamp.

JOHN J. WHINTON.
